CONVEYER

Clarence C. Larsen, Bismarck, N. Dak.

Application February 27, 1941, Serial No. 380,787

7 Claims. (Cl. 198—226)

This invention relates to material handling apparatus and more particularly to mechanism for feeding divided solids such as fuels in a stoker.

In the handling of solid fuels with automatic feed mechanism it generally requires considerable power to force the fuels through the feed tube of the mechanism and into the fire pot. This is due to the frictional characteristics of materials such as coal and other solid fuels, for when such materials are forced through a stoker tube with a ram or screw the materials build up a large amount of resistance to movement.

It is a general object of my invention to provide material handling apparatus such as stokers with means for greatly reducing the frictional drag of fuels as they are forced through feed tubes.

A more specific object of the invention is to provide improved fuel feeding apparatus for stokers which includes an anti-friction shell reciprocating in the stoker tube wherein the shell facilitates forward movement of the fuel and reduces frictional drag against the tube and wherein it can be returned for another forward stroke without disturbing the fuel from the position to which it has been progressed.

Another object of the invention is to provide means for facilitating the feeding of fuel through a stoker feed tube which can be incorporated with an ordinary stoker structure.

These and other objects and advantages of the invention will more fully appear from the following description made in connection with the accompanying drawings, wherein like reference characters refer to the same parts throughout the views, and, in which:

Fig. 1 is a plan view of a stoker and a portion of a burner with which it is associated;

Fig. 2 is a side elevation of the apparatus shown in Fig. 1;

Fig. 3 is an end view with the upper portion of the hopper broken away;

Fig. 4 is a longitudinal vertical section through the lower portion of the hopper and through the feed tube assembly;

Fig. 5 is a sectional view taken approximately on the line 5—5 of Fig. 4;

Fig. 6 is a sectional view taken approximately on the line 6—6 of Fig. 4;

Fig. 7 is a sectional view taken approximately on the line 7—7 of Fig. 4; and

Fig. 8 is a bottom plan view of the ram and my improved feed mechanism.

In the drawings there is shown a furnace fire box wall 9 and a grate 10. The furnace is provided with a casing 11 having a door 12 in its

lower portion. A stoker feed tube 13 is supported at its right-hand end by a stand 14 having leveling legs 15. The other end of the feed tube 13 extends through the door 12 and fire box wall 9 terminating just inside said wall at the upper portion of the slanting row of grate bars 10. A feed hopper 16 is adapted to supply fuel through a suitable inlet opening in the top of the feed tube 13.

A blower casing 17 has an air conduit 18 extending therefrom through the furnace door 12 and lower portion of the fire box wall 9 to a point beneath the grate 10. A blower 19 in the casing 17 is driven by a suitable electric motor 20.

The feed tube 13 has its inlet 13a defined by an upstanding flanged portion upon which rests the hopper 16. The hopper has a plurality of downwardly extending lugs 16a which fit into the feed tube inlet 13a to hold it in position.

The feed tube 13 has a plunger or ram 21 mounted therein for reciprocal movement in the right-hand portion of said tube. The ram preferably has a slanting forward face 21a such as is well known in the stoker art. The ram 21 is connected by a link 22 to a rotary disc 23. The disc 23 has a plurality of openings 24 formed therein to receive a bolt 25. By shifting the bolt 25 to various holes 24 the length of throw of the link 22 can be changed due to the fact that the holes 24 are spaced different distances from the rotational axis of the rotary disc 23. Said disc is suitably driven through a gear box 26 and belt drive 27 by the motor 20. The details of the gearing are not shown since they are not essential. The ram 21 is shown in its retracted position and is adapted to move roughly half the distance across the feed tube inlet 13a, and as the ram is retracted additional fuel falls from the hopper 16 through said feed tube inlet and in front of the ram 21 to be pushed to the left of said feed tube 13.

Mounted in the left-hand portion of the feed tube 13 is an inverted U-shaped anti-friction shell 28 which, as best shown in Fig. 5, lies against the side and upper inner walls of said feed tube 13. The bottom inner wall portion of the feed tube is exposed to the interior space of the tube. The anti-friction shell 28 is best shown in Figs. 4 and 8 to be elongated and connected by means of bars 29 to the ram 21. These may be formed as an integral unit if desired. The right-hand end of the shell 28 is cut away, as best shown in Figs. 4 and 8, to permit fuel to be dropped from the hopper 16 through the feed tube inlet 13a to a point between the ram 21 and the rear end of the upper portion of said shell 28. The left-hand or forward end of anti-friction shell 28 tapers upwardly

towards its forward end and its forward and lower edges are sharpened to permit said forward and lower edges to cut between the fuel and the inner wall of the feed tube 13 as the ram and shell 28 are moved forwardly or to the left.

In operation when fuel is placed in the hopper 16 and a portion thereof falls into the feed tube 13, reciprocation of the ram 21 to the left will push this fuel in the same direction. As successive strokes of the ram 21 push material to the left-hand portion of the feed tube 13, the anti-friction shell 28 moves along with the fuel being forced through the tube and prevents contact of the fuel with the sides and upper inner portions of said feed tube 13. This, consequently, greatly reduces the frictional drag of the fuel on the inner walls of the tube. However, some provision must be made to retain the fuel in its forwardly progressed position, and for that reason the shell 28 is not designed to cover the lower inner wall of the feed tube 13. The weight of the fuel resting upon the bottom of the feed tube 13 holds it sufficiently to prevent backward movement of the fuel when the ram and anti-friction shell 28 are retracted for another working stroke.

Due to the relative ease with which the fuel is worked through the feed tube with the assistance of the shell 28, said fuel does not pack in the feed tube and become even more compressed under action of the ram 21. Instead it is loosely fed along the left-hand end of the tube 13 and flows easily out of the end of the tube and onto the grate bars 16.

From the foregoing description it will be seen that I have provided a stoker mechanism which greatly reduces the amount of power needed to operate a feed member such as a ram or screw and in which the material is fed through the feed tube in a loose unpacked condition so that it feeds freely from the outlet end of the tube to the grate. This results in the ability to make lighter operating parts and it does not require the use of as strong motors or other power sources to provide for effective operation.

While the invention has been described in connection with its use as a stoker, it will be understood that the device described can be used for handling and conveying any type of divided material such as granular, powdered or lump material. It is contemplated for example that the device may be used for conveying grain, gravel, stone, crushed rock, sand, etc. from one point to another.

It will, of course, be understood that various changes may be made in the form, details, arrangement and proportions of the various parts without departing from the scope of my invention.

What is claimed is:

1. Divided solid material conveying means comprising, a conveyer conduit having an inlet and an outlet, means in said conduit adjacent said inlet for forcing said materials through said conduit, and an inverted scoop-like shell element in said conduit having portions positioned adjacent the inner side walls of said conduit, said element being movable with said materials and between said materials and said conduit wall to reduce frictional drag of said materials on said inner conduit wall.

2. Divided solid material conveying means comprising, a conveyer conduit having an inlet and an outlet, a reciprocable ram mounted in said conduit adjacent said inlet and movable from a point substantially beside said inlet to a point at least partially across said inlet, and an inverted U-shaped shell relatively closely fitting side and upper inner wall portions of said conduit, and a connection between said shell and said ram to provide for reciprocable movement of said shell with said ram.

3. In a stoker, a fuel feed tube having a fuel inlet adjacent one end and a fuel outlet at the other end thereof, a reciprocable ram mounted in said feed tube adjacent said inlet, a pair of substantially parallel spaced arms connected to said ram at opposite sides thereof and extending forwardly in said feed tube a substantial distance, an anti-friction shell lying within said feed tube and conforming at both inner and outer sides substantially to the shape of the inner portion of said feed tube at its top and side portions to receive fuel between its side portions, said shell being open adjacent the bottom of said feed tube, and said shell being connected to said arms at the opposite ends thereof from the connection of said arms with said ram.

4. In a stoker, a feed tube having an inlet adjacent one end and an outlet at the other end thereof, a reciprocable ram within said feed tube positioned to progress fuel from said inlet portion of said tube forwardly toward the outlet end of said tube, an anti-friction shell conforming generally to the inner shape of said feed tube at the top and side portions of said tube, said feed tube inlet being located substantially between said ram and said anti-friction shell, connecting means between said ram and said shell to cause reciprocation of said shell with said ram, said shell being open throughout its bottom portion and tapering forwardly, and the lower and forward edges of said shell tapering to a relatively sharp edge.

5. Divided solid material conveying means comprising, a conveyer conduit having an inlet and an outlet, means for forcing material through said conduit and an inverted U-shaped shell closely fitting the side and upper inner wall portions of the conduit, and means for reciprocating said shell.

6. The structure defined in claim 5, said shell at its forward portion tapering to its forward end and the lower and forward edges of the shell being downwardly and outwardly beveled.

7. Divided solid conveying means comprising, a substantially horizontally disposed conveyer conduit having an inlet and outlet and top, bottom and side walls, means for forcing material through said conduit, and a member movable with said material for reducing frictional drag of the material on the conduit walls, said member being open at its bottom and having a top portion working adjacent the top of said conduit and having lateral portions projecting downwardly below said top portion and working between the material and the side walls of said conduit.

CLARENCE C. LARSEN.
